UNITED STATES PATENT OFFICE.

WILLIAM G. DRAKE, OF ADRIAN, MICHIGAN.

IRONING TABLE OR CABINET.

1,203,507.

Specification of Letters Patent.

Patented Oct. 31, 1916.

Application filed March 17, 1916. Serial No. 84,886.

To all whom it may concern:

Be it known that I, WILLIAM G. DRAKE, a citizen of the United States, residing at Adrian, in the county of Lenawee and State 5 of Michigan, have invented new and useful Improvements in Ironing Tables or Cabinets, of which the following is a specification.

My invention relates to certain new and 10 useful improvements in ironing tables or cabinets, the primary object of the invention being to provide a pedestal type of ironing table, wherein the leg or pedestal is designed to be firmly secured to the floor 15 adjacent to a wall or wainscoting, and the top or cabinet portion is pivotally supported upon said leg or pedestal so as to be folded to an out of the way position parallel with the wall or wainscoting or 20 downwardly to a horizontal position for use.

Another object of the invention is to provide a pedestal which is hollow to form a compartment for irons and other accessories used in connection with the table, and 25 which embodies means for firmly supporting the table when in a horizontal position, and means coöoperating with locking devices on the table for firmly locking the table in its two stated positions.

30 Another object of the invention is to provide means upon the pedestal and table back, by means of which when the table is arranged in position for use, the back thereof which supports the ironing board proper 35 will be held firmly against springing under any of the working pressures commonly employed.

Another object of the invention is to provide a table in which the back supporting 40 the ironing board is adapted to be covered and partially inclosed by a top or front section which is hinged or pivoted thereto so as to be swung to a vertical position when the back and board are horizontally disposed for use, and in which simple and effective means for locking the 45 cover or front section in such position is included in the structural organization.

Still another object of the invention is to 50 provide means for detachably securing a reversible board to the back, to provide means for supporting the iron in use upon the cover or top section, to provide a sleeve or bosom board, which iron support and 55 sleeve or bosom board may be adjusted into and out of operative positions, and to pro-

vide other features of construction whereby an ironing table possessing material advantages is produced.

With these and other objects in view, 60 the invention consists of the features of construction, combination and arrangement of parts herein fully described and claimed, reference being had to the accompanying drawings in which:—

Figure 1 is a front elevation of an ironing table embodying my invention, showing the same with the table top turned up, as when the table is not in use. Fig. 2 is a side elevation of the same, the pedestal appearing in vertical section. Fig. 3 is a sectional elevation showing the table let down to a horizontal position for use and as it appears prior to the raising of the cover or top section. Fig. 4 is a vertical longitudinal section showing the table in position for use and with the cover or top section raised. Fig. 5 is a cross section through the base looking upward toward the table top as shown in Fig. 4. Fig. 6 is a vertical 80 transverse section on the line 6—6 of Fig. 4. Fig. 7 is a detail longitudinal section on the line 7—7 of Fig. 6. Fig. 8 is a bottom plan view of the ironing board. Fig. 9 is a sectional elevation on the line 9—9 of Fig. 2. Fig. 10 is a horizontal section on the line 10—10 of Fig. 2. Fig. 11 is a horizontal section on the line 11—11 of Fig. 2. Fig. 12 is a detail transverse section through the supporting bracket upon the table back. Fig. 13 is a detail view of the latch device for coöperation with the latch arm of the cover or top section. Fig. 14 is a detail view 90 of the sliding latch plate thereof.

In carrying my invention into practice, I 95 provide a hollow pedestal 1, made of sheet metal, and preferably in the form of a cylindrical tube, riveted or otherwise suitably secured at its lower end to a base ring or member 2 having a flange 3 for the passage of screws or other fastenings, whereby it may be secured to a floor or other suitable foundation 4. A partition 5 is provided within the tubular pedestal at a point about midway of the length thereof, which subdivides the interior of the pedestal and forms the bottom of a storage chamber 6 in which oils and other accessories used in connection with the table may be stored. The pedestal is adapted to be fastened to the 100 floor or foundation adjacent to the wainscoting or side wall of a room or apart.

ment, and is provided at its top with a head 7, preferably of rectangular or oblong rectangular form, and having an annular flange 8 depending within and secured to the top 5 of the pedestal by means of which the head is firmly fastened thereto. The central portion of the head is provided with an opening 9 giving access to the chamber 6 and adapted to be closed by a lid 10 having a 10 knob or handle 11. The lid 10 lies flush with the top of the head when applied so that the knob or handle will not unduly project.

The head 7 is bifurcated at one side to provide lugs or horizontal knuckles 12 and is recessed or cut away at its diametrically opposite side to form a latch engaging portion 13. As shown, the knuckles 12 project upward from the head, and arranged adjacent 20 to the portion 13, on opposite sides of the longitudinal center of the head, are upstanding supporting lugs or bosses 13' having reduced dowels or projections 14.

The table top 15 consists of two main sections, to wit, a back section 16 and a top or cover section 17, which are combined and co-operate in the manner hereinafter described. Secured to the rear or undersurface of the said back section 16 is a longitudinally extending channeled supporting bracket 18 having a cross piece or portion 19 cast or otherwise formed integral therewith, the said bracket and its cross piece being suitably constructed for firm attachment to the back by screws or other suitable fastening members. The lower end of the bracket, which extends centrally and longitudinally of the back, is provided at its lower or foot end with a pin 20, and at its upper or top 40 end is provided with a pin 21, which pins extend through the webs or flanges of the channeled bracket and pivotally support latch members 22 and 23, the said latch members being pivotally coupled for movement in unison by a connecting rod 24. The free end of the latch member 22 is provided with a beveled nose 25 and a notch 26 for co-operation with a locking slot or opening 27 in the side of the tubular pedestal, by 50 means of which the table top may be locked firmly when disposed in a vertical position, the beveled nose 25 adapting the free end of the latch to tilt up when striking the outer portion of the wall of the opening 27 so that it will pass freely through such opening and then drop by gravity into locking engagement with the lower portion of the wall thereof. When the cabinet or table top is arranged in the position stated, it 55 will be disposed perpendicularly in a plane in advance of the tubular pedestal and will partially conceal the same, and said cabinet or top may be of a suitable character to serve as an ornamental as well as useful 60 article of furniture. The latch 23 has its

outer end extended to form a handle and is provided with a notch 28' for engagement with the portion 13 of the head 7 when the cabinet or table top is disposed in a horizontal position, so as to lock the same firmly 70 and securely in such position.

The cabinet or table top is pivotally mounted upon the head 7 by means of a pivot or hinge rod 28 which engages the knuckles 12 and co-operating knuckles 29 formed upon 75 the ends of the cross piece 19 of the bracket 18, the pivotal connection being so arranged that the cabinet or table top is approximately balanced, allowing it to be swung easily from a vertical to a horizontal position, and vice versa. It will be evident that by depressing the latch 23 when the cabinet or table top is vertically disposed, the latch 22 may be withdrawn from engagement with the keeper slot 27, whereupon the cabinet 80 or table top may be tilted to a horizontal position, in which position the dowels or projections 14 of the lugs 13 engage seats or openings 31 in the back 16, whereby a connection between the back and head is established to firmly hold the back against any tendency to lateral motion. It will thus be evident that a firm support from the top will be provided, and, inasmuch as the bracket 18 and its cross piece are rigid in 95 character and extend practically the entire length of the back 16, the latter will be held from yielding under any pressure exerted upon it during the ironing operation at any point along the ironing surface of the 100 table top.

The back section 16 is adapted to be received and inclosed within and by the rabbeted portion 32 of the side and end walls of the cover or top section 17, which is 105 of proper form to receive and inclose both the back and the ironing board 16' supported thereon, whereby the board is protected from the access of dust and dirt when not in use. When the top or cabinet is swung downward to a horizontal position as stated for use, the top or cover section 17 is swung upward to a vertical position parallel with the wall and between the same and the plane of the pedestal, and is locked and held in 110 such position by means of a longitudinally curved or segmental latched member 33, which is pivoted at its upper end to a pin 34 extending between channel forming flanges 35 on a bracket plate 36 firmly fastened to and within the hinged end of the cover or table top, the said bracket 36 being bifurcated at its lower end to provide hinge knuckles 37 connected by a hinge rod 38 with knuckles 39 on a bracket plate 40 115 fastened to the adjacent end of the back 16 by bolts or other suitable fastening members 41. The lower or free end of the latch 33 passes downward and rearward through a guide slot 42 formed in the back 16 and also 120

through a slot 43 in a combined guide keeper plate 44, which is transversely notched to receive a transversely disposed longitudinally sliding latch plate 45 having a lateral notch

5 46 in one of its longitudinal edges and having at its opposite ends combined handles or finger pieces and stop members 47 and 48.

The lower end of the latch 33 terminates in a stop hook 33' and a notch 49 for co-10 operation with the latch plate 45, it being evident from the construction disclosed that when the notch 46 of the plate 45 is in registry with the slots 42 and 43 the hooked end of the latch is free to move through the slots 15 so that the table top or cover may be raised and lowered without resistance. By however shifting the plate 45 so that the notch 46 will be out of registry with said slots, the hooked end of the latch 33 on the opening

20 movement of the table top or cover will strike an adjacent unapertured portion of the latch plate and will be held from further upward movement, so that by manipulation of the latch 45 said latch may be engaged

25 with the notch 49 to lock the table top or cover in raised position and against any possibility of its accidentally falling. The upper end of the bracket plate 36 is preferably bifurcated to form hinge knuckles 49'

30 for the reception of a pin or pintle 50 which is pivotally engaged by knuckles 51 on a swinging iron holding plate or shelf 52

which is adapted to be swung upward from a position within and parallel with the cover 35 or top section to a position at right angles thereto for use, in which position the said shelf or plate is brought to rest against supporting lugs 53 formed on the bracket 36. Preferably the upper surface of said shelf

40 or bracket is dished or recessed so as to hold the iron or other article supported thereon from slipping off or becoming accidentally displaced.

The upper surface of the back section 16 45 is of proper form and size to support the ironing board 16' which may be of conventional form and which is provided at one end with a central notch 54 and at its opposite end with a pair of notches 55, arranged 50 on opposite sides of its longitudinal center, to respectively receive retaining lugs or projections 56 suitably secured to the back, and with which the notched portions of the board are held in engagement by pivoted 55 turn buttons 57, such fastening means permitting the board to be applied and removed with ease and facility. The board is preferably provided with a fabric covering 58 the longitudinal edges of which extend over 60 upon the back or underside of said board and are provided with eyelets 59 for the passage of a lacing thong 60 by means of which the cover is fastened in position and may be drawn to the desired tension. It will 65 be evident that the construction of fastening

means employed not only adapts the board to be quickly and conveniently applied and removed, but also permits it to be reversed whenever desired or required.

For use in conjunction with the device as 70 thus constructed, I preferably provide a sleeve or bosom board 61 which is disposed at a suitable point upon the rear surface of the back 16, said board being pivotally mounted adjacent one end upon a pivot pin 75 or bolt 62 and having concentric therewith an arcuate slot 63 through which passes a bolt 64 which also passes through the back and is provided with a wing nut 65, whereby the sleeve or bosom board may be swung 80 outward from behind or beneath the back 16 to a greater or less angle thereto for use, as will be readily understood.

From the foregoing description, taken in connection with the accompanying drawing, 85 the construction and mode of use of my improved pedestal, ironing cabinet or table will be readily understood, and it will be seen that the invention provides a device of this character which is comparatively simple of 90 construction and inexpensive of production, and which at the same time affords the manifold conveniences stated and provides an article which is stanch and durable and may be made as ornamental and attractive 95 as desired.

I claim:—

1. In an ironing table, a supporting pedestal, a supporting member at the top of the pedestal, a table hinged to and at one 100 side of said supporting member, and means carried by the table to interlock with the diametrically opposite side of said supporting member to hold the table in a horizontal position for use.

2. In an ironing table, a pedestal, a table pivoted to the pedestal, and latches upon the table for engagement with the pedestal to hold said table in vertical and horizontal positions respectively.

3. In an ironing table, a pedestal, and a table comprising a back and a cover hinged thereto, an ironing board mounted upon the back, and locking means upon the table engageable with the pedestal to secure the table 115 in vertical and horizontal positions.

4. In an ironing table, the combination of a supporting pedestal having a keeper slot in its side and having a head provided with a keeper portion, a table pivoted to said 120 head and comprising a back, a cover and a board secured to the back, said cover being hinged to the back, and latches pivoted to the table and adapted for respective engagement with said keeper opening and keeper portion, said latches being connected for movement in unison and one being manually operative for shifting the other into and out of locking engagement.

5. In an ironing table, a supporting 125

pedestal having a keeper opening in its side, a head carried by the pedestal and having dowels at one side and a keeper portion between said dowels, an ironing board pivoted to the head, latches upon the board to engage the keeper opening and keeper portion, said table being provided with seats to receive said dowel pins when the table is disposed in a horizontal position, and a connection between said latches for their adjustment in unison.

6. In an ironing table, a supporting

pedestal, a table hinged to the pedestal, means for locking the table in horizontal and vertical positions, a hinged cover for the table, and means for locking said cover in an open position.

In testimony whereof I affix my signature in presence of two witnesses.

WILLIAM G. DRAKE.
